UNITED STATES PATENT OFFICE

WILBUR G. LAIRD, OF NEW YORK, N. Y., ASSIGNOR TO HEAT TREATING COMPANY, OF NEW YORK, N. Y., A CORPORATION OF DELAWARE

BUBBLER CAP CONSTRUCTION

Application filed March 5, 1930. Serial No. 433,246.

This invention relates to improvements in bubble cap column construction and more particularly to a construction wherein the bubble cap may be completely removed from 5 and easily attached to the tray of the bubble cap column.

This construction is particularly adapted for use in rectifying columns in which petroleum vapors are intimately contacted with 10 liquid petroleum but it may also be used in other arts for intimate contact of gas and liquids, such as distillation, saturation, chemical reaction, gas scrubbing and for various other purposes.

15 The present method of constructing a complete bubble cap tray involves, along with a useless and extraordinary waste of time, a great deal of unnecessary labor, and is unnecessarily troublesome. In the usual method 20 of construction, the column is erected with the trays in place, the vapor riser pipes and the caps not having been previously fitted. It is necessary for a man to enter the column and to permanently attach the pipe and caps 25 by rolling, bolting, or other method, or as in the case of a column with removable bubble caps for two men to work in the column, one above and one below the tray.

30 One of the chief objects of the present invention is to overcome these defects and objections by providing an easily attachable riser pipe and bubble cap proper which will, with slight effort and minimum trouble take but a small fraction of the time to install, as 35 has heretofore been necessary.

It has also been found that in various processes of rectification, distillation, and gas scrubbing the bubble caps tend to clog up or corrode, thus impairing the efficient operation 40 of the apparatus. They therefore must be cleaned by hand which in the ordinary construction means a loss of operating time and extra expense for cleaning, since in most cases 45 the caps are not readily removable.

Accordingly, another object of this invention is to overcome the above objection by making the bubble caps easily removable so that it will be a quick and a simple matter 50 to clean the caps and pipes and thus to put

the apparatus in condition for another run in a comparatively short time.

Another advantage of this invention is that the complete bubble cap referred to may be manufactured or cast on a large scale 55 without regard to slight variations in the thickness of the tray and other dimensions which it is usually necessary to ascertain with precision in the manufacture of bubble caps.

Other objects and advantages of the invention will be apparent from the following detailed description taken in connection with the accompanying drawing, in which:

Fig. 1 is a top plan view of a portion of a bubble cap column tray showing a single 60 bubble cap, part of the cap being broken away to show the lower construction thereof;

Fig. 2 is a vertical sectional view of a portion of the bubble cap column tray showing the structure of a single bubble cap and related parts;

Fig. 3 is a vertical sectional view of a portion of the bubble cap showing a modified form of construction.

Referring to Fig. 2 of the drawing, 2 indicates a portion of a bubbler tray in which are the usual openings 4 to accommodate vapor riser pipes. In accordance with the present invention a vapor riser pipe 6 is provided with a shoulder 8, which is machined 75 to rest upon and sit in the opening 4 in tray 2, giving a substantially gas tight but easily removable connection as at 10. Extending over the riser pipe 6 and resting on the shoulder 8 thereof by means of brackets 80 12 is a bubble cap proper 14. This cap, a one piece casting in the usual form, which extends over and incloses the upper portion 85 of the riser pipe, contains the usual serrations 16, in the lower edge thereof, brackets 12 fashioned so that the cap 14 will rest firmly on the shoulder 8 in a substantially horizontal position and an indicator 18, the purpose of which will be set forth hereinafter. The cap is bored off center through a shoulder 90 20 to accommodate a locking bar 22. The shoulder 20 serves to maintain the bar substantially parallel to the sides of the cap. On the bar 22 and formed as a part thereof is a nib 23 positioned slightly below the 95 100

shoulder 20 of the cap. This nib prevents the bar from sliding through the shoulder and possibly being bent out of alignment while the caps are being handled for shipment or installation. The locking bar is bent at the lower end thereof at an angle of more than 90° with respect to the axis of the bar so that in one position in respect to the cap it will engage with the bottom of the bubbler tray as at 24, the resilience of the bar allowing it to be turned until the parts of the bubble cap are firmly clamped together and to the tray 2. In the opposite position the locking bar will be totally disengaged from the tray, and, on raising the bubble cap proper, the bar may be completely lifted through the riser pipe. Mounted upon the cap 14 and loosely fitted thereto by means of corrugated surfaces 26, is a handle or operating member 28 which is attached to the locking bar 22 by means of a cotter pin 32. The handle 28 is provided with a pointer 30.

The improved bubble cap as above described is installed in the following manner: The vapor riser pipe 6 is placed in position in the opening 4 in the bubbler tray 2 with the shoulder 8 resting firmly on the tray, and the bubble cap proper 14, is placed over the vapor riser pipe with the brackets 12 resting on the shoulder 8. During this time the locking bar 22 is kept in a disengaged position as shown in the drawing, which position is indicated to the operator by the point 30 on the handle coinciding with the indicator 18. The bubble cap is now in position and a quick turn of the handle, until the bubble cap is firmly clamped to the tray, locks all parts of the apparatus in place.

The corrugated surfaces 26 will allow a relatively free movement between the handle 28 and the bubble cap proper 14, when the locking bar is not engaged. However, when the locking bar is engaged with the underside of the bubbler tray the corrugated surfaces will grip each other and tend to hold the bubble cap in a locked position, thus preventing it from working loose. Inasmuch as the bubble cap must withstand many vibrations which may have a tendency to work the cap loose this feature of the present invention is very desirable.

The trays of the bubble cap column which are provided with the improved bubble cap constructed in accordance with the present invention may be cleaned in the following way: After the column has been shut down the manhole above each tray may be opened and a few caps removed on each tray. The various bubble caps are loosened by turning the handles on the caps until the locking bars are in the disengaged position and the caps and riser pipes are then removed. If the riser pipes tend to stick in the openings 4 they may be easily knocked loose with a mallet. The trays may then be cleaned by

flushing down any extraneous matter through the openings onto the tray below beginning with the top tray in the column. The caps may be cleaned in any suitable manner and replaced as previously described.

It is a simple matter to replace bubble caps now in use with those made in accordance with the present invention, since the only operation necessary for replacing after removal of the old caps and risers from the trays is to insert the improved riser pipes in the openings already in the tray and assemble as described above. The caps proper may also be used without removal of old riser pipes. It will be seen that the improved bubble cap is adaptable to any tray regardless of the slight variations in the thickness of the tray, because the bent end of the locking bar 22 is at an angle such that any change in tray thickness merely changes the degree of turn to be given to the handle. Consequently, this peculiarity may be disregarded when using the bubble cap which is the subject of the present invention.

In the modified form of construction shown in Fig. 3 the handle 28 is omitted and the locking bar 22 is formed with a square shank 34 on the upper end thereof to permit the locking mechanism to be operated with a wrench or detachable handle. In this construction a square holed washer 36, fitted to the shank 34, and a cotter pin 38 hold the locking bar 22 in place and prevent it from slipping through the shoulder 20. The underside of the washer is formed with corrugations so as to loosely fit with the corrugations on the bubble cap proper. The corrugations on the washer 36 function the same as the corrugations on the attached handle as previously described. This modified construction may be operated in substantially the same manner as the apparatus heretofore described but it has an additional advantage in that there will be a lessened possibility of breakage of the parts during shipment due to the omission of the handle.

Unless otherwise indicated it is to be understood that by the term "bubble cap proper" is meant that part overlying and resting on the shoulder of the vapor riser pipe, including the locking arrangement, and by the term "bubble cap" is meant the complete bubble cap including the riser pipe and the cap proper with the locking arrangement.

Having described the invention in its preferred form what is claimed as new is:

1. In a gas and liquid contact apparatus in which a bubble cap extends over a riser pipe fitted in an opening in the bubbler tray, the improvement which comprises a hand-operable locking mechanism, the operating means of which lies entirely above the cap, said mechanism being adapted to simultaneously and firmly secure the riser pipe and cap to the tray.

- tray with less than a complete revolution of the operating means.
2. In a gas and liquid contact apparatus in which a bubble cap extends over a riser pipe fitted in an opening in a bubbler tray, the improvement which comprises an off-center resilient locking member attached to said cap and having a portion adapted to be swung into engagement with the underside of said tray, or disengagement therewith, by rotating the member about the axis of its point of attachment to said cap.
3. In a gas and liquid contact apparatus in which a bubble cap extends over a riser pipe fitted in an opening in a bubbler tray, the improvement which comprises an off-center hand-operable locking member attached to said cap and having a portion so arranged as to simultaneously and firmly secure the riser pipe and cap to the tray or to completely release the riser pipe and cap from the tray according to the radial position of said portion of said locking member.
4. In a gas and liquid contact apparatus in which a bubble cap extends over a riser pipe fitted to an opening in a bubbler tray, the improvement which comprises a hand-operable locking member attached to said cap, and having a portion adapted to firmly secure the cap to the tray over the riser pipe, said locking member comprising an element adapted to be swung into engagement with the underside of said tray.
5. In a gas and liquid contact apparatus in which a bubble cap extends over a riser pipe fitted to an opening in a bubbler tray, the improvement which comprises an off-center locking member attached to said cap and having a portion so arranged as to engage or completely disengage the underside of said tray according to the radial position in which said portion of said locking member is placed, and means adapted to utilize the tension in said locking member to hold said member in locked position in engagement with said tray.
6. In a gas and liquid contact apparatus in which a bubble cap extends over a riser pipe fitted in an opening in a bubbler tray, the improvement which comprises a hand-operable locking bar attached to said cap, said bar being bent at its lower end and adapted to simultaneously and firmly secure the riser pipe and cap to the tray.
7. In a gas and liquid contact apparatus in which a bubble cap extends over a riser pipe fitted to an opening in a bubbler tray, the improvement which comprises a locking bar attached to said cap, the lower end of said bar being bent at an angle of more than 90° with respect to the axis of said bar, said bar being adapted to firmly secure the cap to said tray over said riser pipe.
8. In a gas and liquid contact apparatus in which a bubble cap extends over a riser pipe fitted to an opening in a bubbler tray, the improvement which comprises an off-center locking bar attached to said cap, said bar being bent at its lower end and adapted to firmly secure the cap to the tray over said riser pipe.
9. In a gas and liquid contact apparatus in which a bubble cap extends over a riser pipe fitted in an opening in a bubbler tray, the improvement which comprises an off-center locking bar attached to said cap, said bar being bent at its lower end at an angle of more than 90° with respect to the axis of said bar and adapted when rotated into locking position to simultaneously and firmly secure the riser pipe and cap to said tray.
10. In a gas and liquid contact apparatus in which a bubble cap extends over a riser pipe fitted to an opening in a bubbler tray, the improvement which comprises a locking bar attached to said cap, said bar being bent at its lower end and adapted to firmly secure the cap to the tray over the riser pipe, and means for holding said cap in a locked position.
11. In a gas and liquid contact apparatus in which a bubble cap extends over a riser pipe fitted to an opening in a bubbler tray, the improvement which comprises an off-center locking bar attached to said cap, the lower end of said bar being bent at an angle of more than 90° with respect to the axis of said bar and adapted to firmly secure the cap to said tray over said riser pipe, and means for holding said cap in a locked position.
12. A bubbler cap construction comprising a bell-shaped member extending over a riser pipe in a bubbler tray, a rotatable locking bar attached to the upper portion of and extending through said bell-shaped member, said bar being bent at its lower end at an angle of more than 90° with respect to the axis of said bar and adapted, when the bar is rotated to engage the underside of said tray, and means for holding said bar in a locked position.
- In testimony whereof I affix my signature.
